UNITED STATES PATENT OFFICE

139,533

DESIGN FOR A REFRIGERATOR

George W. Walker, Pleasant Ridge, Mich., assignor to Bohn Aluminum & Brass Corporation, Detroit, Mich., a corporation

Application September 1, 1943, Serial No. 111,043

Term of patent 3½ years

(Cl. D67—3)

To all whom it may concern:

Be it known that I, George W. Walker, a citizen of the United States of America, residing at Pleasant Ridge, in the county of Oakland and State of Michigan, have invented a new, original, and ornamental Design for a Refrigerator, of which the following is a specification, reference being had to the accompanying drawing, forming a part thereof, wherein:

Fig. 1 is a perspective view of a refrigerator embodying my new design; and

Fig. 2 is a plan view of the top of the refrigerator, on a reduced scale.

Part of one of the glass panels has been broken away in order to show certain of the interior parts of the refrigerator which are visible through the glass panels from the front of the refrigerator.

The rear of the refrigerator is plain and unornamented and the other side is like the side illustrated.

I claim:

The ornamental design for a refrigerator, substantially as shown and described.

GEORGE W. WALKER.
